DEVICE FOR SPOOLING REDA AND LIKE CABLE

Borger L. Opsal, Oklahoma City, Okla., assignor, by direct and mesne assignments, of one-half to Cities Service Oil Company, Bartlesville, Okla., a corporation of Delaware

Application August 22, 1940, Serial No. 353,602

6 Claims. (Cl. 254—135)

This invention relates to spooling devices, and more particularly to devices of that character wherein the power to drive the same is derived from a source that is ordinarily employed for another purpose.

The principal object of the present invention is to provide a convenient, relatively economical and highly efficient spooling device.

A particularly useful application of the invention is in spooling Reda cable from oil and like wells. Reda cable is known in the oil industry as a flexible, tough, electric current conducting cable that supplies an electric pump on the bottom of tubing in a well with energy for its actuation. The pump, in turn, communicates the tubing with fluid in the well and forces the fluid from a well shot hole, for example, up the tubing to the earth's surface for suitable disposition. The Reda cable is ordinarily run into and out of the well along with the tubing exteriorly thereof, and is suitably secured thereto. When, therefore, the tubing is pulled, the Reda cable is usually removed from the well simultaneously therewith. Due, largely, to the character of the cable, that is, the strength required of it, it is usually of such diameter and rigidity as to be relatively unwieldy. It is desirable, however, to arrange the cable, when spooled, adjacent the well and preferably near a derrick floor or gin-pole support, where such apparatus is employed for applying and pulling tubing.

Other objects of the invention are, therefore, to provide for spooling cable and the like, such as Reda cable, at or near its scene of intended operations; to provide for spooling cable and the like with facility, in a relatively compact mass and in a condition in which it is readily available for use; to provide an improved reel rotation adjusting mechanism wherein speeds of rotation thereof may be varied relative to speed of movement of tubing as it is being lowered or raised into or out of a well; to provide a novel braking effect for a reel; to provide a power-take-off peculiarly suitable for spooling devices employed in conjunction with and/or as an adjunct to tubing pulling apparatus; to combine a cat-head with a driven sheave or the like for providing a drive from the cat-head; and to provide improved elements together with arrangements thereof in a spooling device of the character and for the purposes noted.

In accomplishing these and other objects of the invention I have provided improved details of structure, the preferred form of which is illustrated in the accompanying drawings, wherein:

Fig. 1 is a side elevational view of a spooling device embodying the features of the present invention, the same being illustratively arranged near a derrick and deriving its drive in the first instance from a tubing pulling unit, a portion of the spooled element being shown in a well, the well being shown in vertical cross-section.

Fig. 2 is a plan view of my improved spooling device and a horizontal section through the derrick illustrated in Fig. 1.

Fig. 3 is a detail perspective view of the power take-off and combination pulley block and cat-head forming a part of this invention.

Fig. 4 is a vertical, substantially central cross-section through the device illustrated in Fig. 3.

Referring more in detail to the drawings:

1 designates a spooling device embodying the features of the present invention, which spooling device preferably consists of a reel 2 that is rotatably mounted on a suitable base 3, preferably in spaced relation to a derrick floor 4, as by standards 5. The reel 2 is preferably provided with suitable means 6 for supplying and transferring electric current between the reel and a cable 7 that is adapted to be wound and unwound relative to the reel responsive to rotation of the reel in opposite directions.

20 The cable 7 may be, and in the present instance preferably is, a "Reda" cable that extends at one end from the reel 2 over a pulley block 8 that is suitably supported, for example, on a structural member 9 of a derrick 10, preferably in vertically spaced relation to the floor of the derrick. From the pulley block 8, the Reda cable extends through an opening 12 in the derrick floor into the casing 13 that is arranged in a well 14 over which the derrick is erected.

30 The casing 13 is suitably supported on a base 15 for the derrick, the casing being provided with suitable apparatus, not shown, for supporting tubing or the like 16 in the casing. The Reda cable may be, and preferably is, secured to the tubing exteriorly of the tubing as by suitable clamps 17, and terminates at a motor 19 for driving a pump 20 to transfer fluids in the well 14 through tubing 16 to the surface of the earth for suitable disposition.

40 When, for any reason, the tubing is to be removed from the well, as for repairs or replacement, suitable apparatus is provided to pull the tubing from the well. Such apparatus ordinarily consists of an elevator 21 engaged with a travelling block 22 as by a connecting device 23. The tackle for the travelling block 22 comprises a pull 55 line 24 that passes over a suitable crown-block

assembly 25 on the derrick, and preferably under a floor-block unit 26.

The floor-block unit 26 forms an important part of the present invention and preferably consists of a block 27 proper, Figs. 3 and 4.

The block 27 preferably comprises spaced side members 29 and 30 that are provided on their inner faces with suitable bearing sheets 31 and 32. The side members and sheets are also provided with aligned pairs of apertures adjacent their upper and lower ends for receiving connecting devices 33 and 34. A spacer 35 is preferably mounted on the lower connecting device 34, and an anchoring member 36 is preferably mounted on the upper connecting device 33, the anchoring member preferably consisting of arms 37 and 38 having aligned apertures 39 and 40 for mounting a tie member 41, Fig. 1, that is secured to the anchoring member at one end and to the derrick at its other end, as indicated at 42, for supporting the floor block. The lower connecting device 34 is preferably provided with a tie member 43 that extends from the pulley block downwardly through an opening 44 in the derrick floor into suitable supported engagement with the derrick base 15.

The side members of the pulley block are also provided with aligned bearing elements 45 and 46 for rotatably supporting a shaft 47. A pulley, sheave, or the like, 48 is mounted on the shaft 47 between the side members of the pulley block and secured thereto as by a key and slot connection 49.

The shaft 47 extends laterally of one of the side members of the pulley block a distance sufficient to form a support for a cat-head 50 on the outer end thereof, which cat-head may be secured to the shaft as by a key and slot connection 51.

The cat-head preferably consists of a drum having a groove 52 for receiving a driving connection, such as a rope or the like 53 that connects the cat-head with a pulley 54 on the reel 2.

The connection between the cat-head and reel pulley is preferably loose enough to allow for slippage therebetween. In order to provide a driving connection between the cat-head and reel a tensioning device 55 is applied to the driving connection 53 of such a character as to apply tension to the connection, overcome the normal slip and rotate the reel in response to rotation of the cat-head.

The tensioning device 55 may, and in the present instance preferably does, consist of a snatch-block over which one end of the driving connection 53 travels. The snatch-block is preferably mounted on the derrick floor, as by a pin 56, a spring 57 being preferably provided on the pin to normally tend to move the snatch-block downwardly for relieving tension on the driving connection.

In order to apply tension of desired strength to the driving connection, the snatch-block is provided with a hook or the like 58, and a connecting device 59 is secured to the hook and passes over a pulley block 60 that may be secured to the derrick. The preferable arrangement of the connecting device 59 is to provide an end 61 thereof in exposed condition to allow it to be grasped and pulled upon to overcome the tension of the spring 57 and thus apply a desired amount of tension to the driving connection 53 to run the reel 2 in desired relation to the cat-head.

The operation of an apparatus constructed as described is as follows:

Assuming a well to be provided with casing,

tubing and a derrick substantially as shown, and that the tubing is provided with Reda pump and cable; when the tubing is to be pulled a suitable elevator is applied to the tubing and 5 operated by the pull line 24. The pull line runs under the floor-block 27 and operates the cat-head 50. With the Reda cable passing over the pulley block 8 and connected with the reel 2, the driving connection 53 may be applied to 10 the pulley 54 on the reel 2 and to the cat-head 50 on the block 27, preferably with a loose enough 15 fit to provide slippage. Tension may then be applied to the driving connection as and when desired by applying tension to the snatch-block 16 55 as by drawing on the snatch-block through the end 61 of the connecting device 59 to overcome the slip. Then, as the pull line 24 moves to raise or lower the tubing relative to the well, the pulley of the block 27 is rotated, the cat-head also rotating to, in turn, rotate the reel 20 and spool or unspool the Reda cable relative to the reel.

It is apparent, therefore, that a convenient, 25 relatively economical and highly efficient spooling device having the characteristics and advantages above set forth has been provided by the present invention.

What I claim and desire to secure by Letters Patent is:

30 1. In an apparatus of the character described comprising a derrick arranged over a well having tubing therein and a cable engaged with said tubing exteriorly thereof, a pulling line engageable with said tubing for removing the same from the well, means for actuating said pulling line, a reel for said cable, a pulley block having a pulley engaged with said pulling line and rotatable in response to movement thereof, said pulley block having a cathead connected to said pulley, means connecting said cathead and reel 35 for driving said reel in response to movement of said pulling line, and means for effecting release of said connecting means whereby said pulling line may be actuated independently of the reel.

40 2. In an apparatus of the character described comprising a derrick arranged over a well having tubing therein and a cable engaged with said tubing exteriorly thereof, a pulling line engageable with said tubing for removing the same from the well, means for actuating said pulling line, a reel for said cable, a pulley block having a pulley engaged with said pulling line and rotatable in response to movement thereof, said 45 pulley block having a cathead connected to said pulley, means connecting said cathead and reel for driving said reel in response to movement of said pulling line, a snatch-block frictionally engageable with said connecting means, and means for moving said snatch-block toward and away from said connecting means to adjust said connecting means for varying the drive of said pulling line relative to said reel.

60 3. In an apparatus of the character described comprising a derrick arranged over a well having tubing therein and a cable engaged with said tubing exteriorly thereof, a pulling line engageable with said tubing for removing the same from the well, means for actuating said pulling line, a reel for said cable, a pulley block having a pulley engaged with said pulling line and rotatable in response to movement thereof, said pulley block having a cathead connected to said pulley, means loosely connecting said cathead and reel, means engageable with said

connecting means to tighten the same relative to said cathead and reel for driving said reel in response to movement of said pulling line, and means acting on said tightening means normally tending to loosen said connecting means for causing slip between said reel and line.

4. In an apparatus of the character described, a cable, means for spooling said cable, a pulley block having a pulley, a cathead on said pulley block and driven by said pulley, means loosely connecting said spooling means with said cathead, means engageable with said connecting means to tighten same relative to said cathead and spooling means for spooling said cable in response to actuation of the pulley of said pulley block, said last named means including an adjustable snatch-block, and resilient means acting on said snatch block for normally tending to loosen said connecting means for causing slip in the connection between said spooling means and the cathead.

5. In an apparatus of the character described comprising a derrick arranged over a well having tubing therein and a cable engaged with said tubing exteriorly thereof, a pulling line engageable with said tubing for removing the same from the well, means for actuating said pulling

line, a reel for said cable, a pulley block having a pulley engaged with said pulling line and rotatable in response to movement thereof, said pulley block having a cathead connected to said pulley, means for selectively connecting said cathead and reel for driving said reel in response to movement of said pulling line, and means for supplying and transferring electric current between said reel and cable.

6. In an apparatus of the character described, an operating mechanism, a cable engaged with said mechanism, a pulling line engageable with said mechanism for moving same, means for actuating said pulling line, a reel for said cable, a pulley engaged with said pulling line and rotatable in response to movement thereof, said pulley having a cathead connected thereto, means loosely connecting said cathead and reel, a snatch-block having a pulley engageable with said connecting means to tighten the same relative to said cathead and reel for frictionally driving said reel in response to movement of said pulling line, and a spring acting on said snatch-block normally tending to loosen said connecting means for causing slip between said reel and cathead.

BORGER L. OPSAL.
